LUGGAGE CARRIER AND SADDLE BASKETS
UNIT FOR A BICYCLE OR THE LIKE

Ruben L. Pawsat, P.O. Box 619, Maysville, Ky.

Filed Nov. 2, 1959, Ser. No. 58,146

Term of patent 14 years

(Cl. D90—3)

FIG. 1

FIG. 3

FIG. 2

Fig. 1 is perspective view of a luggage carrier and saddle baskets unit for a bicycle or the like showing my new design;

Fig. 2 is a top plan view thereof; and

Fig. 3 is a rear elevational view thereof in an inverted position.

I claim:

The ornamental design for a luggage carrier and saddle baskets unit for a bicycle or the like, as shown.
